UNITED STATES PATENT OFFICE.

FRANK K. HOOVER AND ARTHUR J. MASON, OF KANSAS CITY, MISSOURI.

EXCAVATING APPARATUS.

SPECIFICATION forming part of Letters Patent No. 679,505, dated July 30, 1901.

Application filed March 29, 1897. Serial No. 629,740. (No model.)

To all whom it may concern:

Be it known that we, FRANK K. HOOVER and ARTHUR J. MASON, citizens of the United States, residing at Kansas City, in the county 5 of Jackson and State of Missouri, have invented certain new and useful Improvements in Excavating Apparatus, of which the following is a full, clear, and exact description, reference being had to the accompanying 10 drawings, which form a part of this specification.

Our invention relates to improvements in excavating apparatus of that class or type commonly known as "dredging-scoops," and 15 may be broadly defined as a power pick-up, wherein the apparatus is ordinarily swung from a derrick-boom or other support and by means of power transferred from the hoisting-engine by cables or chains may at the will 20 of the operator be lowered or raised, opened or shut, and so constructed and arranged that in its closing operation it may grasp the material to be handled, whether earth, stone, coal, ore, lumber, or any other material. We 25 have found that in order to obtain the best results in the operation of a device of this character the particular manner in which the two principal members of the scoop are caused to approach each other in the loading opera- 30 tion is of primary importance. Heretofore, so far as we are aware, the two opposing shells or trays of the scoop have been united to each other and to a hoisting cable or chain in such a manner and in such relation as that the cutting 35 edges of the scoops or trays ordinarily move through arcs of circles or other paths of a more or less pronounced curvature between their opening and closing extremes. We have found by numerous experiments that 40 the best results in excavators of this character are to be obtained when the scoops or trays are given a very slightly-curved path of movement during the major part of their travel from the closed to the open position, 45 the same more nearly approaching a horizontal path, and at or near the outer limit of their opening movement and the beginning of their closing movement are tilted abruptly, so that their bottom surfaces present a con- 50 siderable angle to the horizontal. In giving this peculiar movement to the scoops we have also found it advantageous to cause the latter

to substantially maintain a persistent angle of inclination to the horizontal during the major portion of their travel in both opening and closing. Such a movement imparted to the scoops enables them most advantageously to penetrate, plow, or cut earth or soil, producing a long plowing-like action adapted to gather up rock, coal, ore, and lumpy material from 60 a large area at a shallow depth, and in handling single pieces of rock or lumber affording a closing grasp of great power, so that the same may be safely lifted and transported.

To the above ends our invention resides in 65 certain features of construction of a device of the character specified, all as hereinafter described and pointed out in the claims, whereby the peculiar and advantageous movements and operation of the trays or scoops hereinbefore referred to are secured.

In the accompanying drawings, which illustrate the preferred form of our invention, Figure 1 is a side elevation of the apparatus with the trays closed. Fig. 2 is a 75 plan view of the same. Fig. 3 is a side elevation of the apparatus with the trays open at the point of dumping, showing in dotted lines the path and inclination of the trays in opening and closing. Fig. 4 represents in 80 diagram the general form in which a cut is made by our improved excavator, the dotted lines showing the different cuts which may be effected by varying the inclination of the trays. Fig. 5 is a perspective detail of the 85 trays in their closed position. Fig. 6 is a detail in side elevation of the trays and the principal and auxiliary lever-arms connected therewith, the trays being shown in an intermediate position between their closed and 90 open positions; and Figs. 7 and 8 are views in side elevation illustrating different positions of the trays intermediate the extremes of their travel.

In the drawings, A represents the trays, 95 the form of which is plainly shown in Fig. 5, the same being oppositely disposed and having their cutting edges arranged adjacent each other, as usual in this class of devices.

B represents the principal lever-arms piv- 100 oted together at J and at their lower ends piv- otally connected with the trays at b'. These arms B are preferably given the curved for- mation shown in the drawings, and it will be

observed that they cross each other between their points of pivotal connection with each other and with the trays somewhat after the fashion of a pair of shears.

5 C represents what we term the "auxiliary arms," the same being pivoted at their lower or outer ends to the trays at c at points in rear of the pivotal connections of the arms B therewith, and each arm C is pivotally connected at its inner or upper ends at c' with the proximate portion of the oppositely-disposed principal lever-arm B. By means of this peculiar connection and arrangement of the auxiliary arms C relatively to the trays and the principal arms B we are enabled to secure a peculiar travel and operation of the trays, as will be hereinafter more fully described. As a means for effecting the opening of the trays thus hinged together we have devised the following mechanism: H' H⁴ and H² H³ represent a pair of toggles which are pivotally connected together at their outer ends by pivot-bolts k³ and k⁴. The outer ends of the toggles are connected with the trays A by means of arms K and K', as clearly shown. The toggle H' H⁴ has its knee disposed coincident with the hinge J of the principal lever-arms B, while to the knee h' of the opposite toggle H² H³ is secured a hoisting-cable L. In order to secure the simultaneous and equal movement of the said toggles toward and past each other in the operation of opening the scoop, the arms H' and H³ of the toggles are extended beyond the pivotal points J and k⁴, as shown at h² and h³, respectively, the latter extensions being connected at their outer ends by a bar H⁵, which lies parallel with the arm H⁴ at all relative positions of the toggles, and by its action causes an equal and opposite movement of the toggles toward and from each other when the trays are opened and closed.

From the foregoing construction and relative arrangement of the operating parts it will be seen that an upward draft on the cable L will, through the weight of the trays and their load, cause a relative downward travel of the hinge J, during which movement the trays will be gradually opened or separated, occupying successively the positions shown in dotted lines at z y x and in full lines in Fig. 3.

The closing of the trays is effected through an upward draft on a closing-cable D, operating upon the trays through the following-described mechanism: E and F designate corresponding arms of a pair of toggles, the outer ends of which are pivotally connected to the noses of the trays A, as at e, and to the upper or inner ends of the principal lever-arms B, as at f. At or near the knees of the toggles E F are mounted on shafts G G' a pair of sheaves d² and d³, and on the hinge-bolt J or on a becket d', secured thereto, is mounted a third guide-sheave d, over which sheaves d, d², and d³ passes the closing-cable D, the

lower end of said cable being secured to a fixed point adjacent to sheave d³. It will be readily seen from Fig. 3 that a hoisting strain 70 on the cable D will draw the sheaves d² d³, and consequently the trays, together to the closed position shown in Fig. 1 with an energy greater than the strain on the cable D in proportion to the number of sheaves on 75 the shafts g and G' or to the number of turns of the hoisting-cable around and between said sheaves.

In operation the apparatus is suspended upon the cable L, which causes it to assume 80 the open position shown in Fig. 3, and is lowered to its loading position. Cable L is then slackened and the power transferred to cable D, whereby the apparatus is closed and loaded and is then elevated and transported 85 to the dump. The power being then again transferred from cable D to cable L, the apparatus is automatically opened, the dump made, and the device is ready to be again returned, lowered, and loaded, as before. 90

Figs. 7 and 8 illustrate in full lines the positions of the trays and their operating mechanism in the opening and closing operations intermediate the extreme positions illustrated in Figs. 1 and 3. An examination of Figs. 1, 95 7, 8, and 3 in the order named and in the converse order will reveal the peculiarity of movement and action of the trays and their operating devices in the opening and closing operations, respectively, as hereinabove referred to in the opening paragraphs of this specification. From these figures, as well as from the dotted-line positions of the trays indicated in Fig. 3, it will be observed that the trays through the major part of their opening and closing travel are held and carried at a substantially persistent inclination to a horizontal line and at a relatively acute angle thereto as compared with the line of travel of the trays or scoops in prior devices of this 100 character. It will be observed that this persistence of inclination of the trays is due to the arrangement and action of the auxiliary arms C relatively to the principal lever-arms B, it being apparent that in the opening movement, as the principal arms B spread to carry the trays apart and in so doing tend to tilt the trays from their initial position, the auxiliary arms C act upon the rear ends of the trays to prevent such tilting and preserve the inclination. This preventive action of the auxiliary arm C continues until substantially the degree of opening shown in Fig. 8 is reached, when in passing from the point shown in Fig. 8 to that shown in 115 Fig. 3 by the action of the auxiliary arms C the trays are abruptly tilted to effect the dump. Likewise in closing, at the beginning of the closing movement by the action of the auxiliary arms C the trays are rapidly 120 tilted from the nearly-vertical dumping position shown in Fig. 3 to the inclination best adapted to cutting and taking up the load, as shown in Fig. 8, and by said auxiliary arms C 125

are prevented from further tilting and are held and retained at said desirable cutting and loading inclination.

The reason for the peculiar movement of the trays hereinabove described is found in the manner of connecting each tray to the proximate portion of the opposing principal lever-arm through the auxiliary arm C. It will be observed that the latter is pivoted to the tray at a point *c* in rear of the pivotal connection *b'* of the principal lever-arm therewith. As now the tray moves outwardly from its closed to its extreme open position, the two pivotal points *c* and *b'* are carried outwardly and upwardly through lines of travel which remain substantially parallel through the major part of the opening movement. This being the case there is no tendency on the part of the tray to tilt, and it is held at a substantially persistent angle of inclination to the horizontal. During the latter part of the opening movement the outer travel of the point *c* is stopped and for a brief space the point *c* even moves inwardly toward the hinge *J*; but in the meanwhile the outer travel of the point *b'* continues in a gradually-increasing ratio to the degree of divergence of the principal arms B, the obvious result of this simultaneous pull of the heel of the tray and outward thrust of its nose being an abrupt tilting of the tray, as hereinabove described, in a manner most favorable for the effective dumping of the load. The converse of this action obviously takes place between the commencement and conclusion of the closing movement, the trays entering the material to be removed at a most advantageous angle for penetration and being immediately thereafter shifted to an angle most effective for the cutting and scraping operation.

According to the proportions and arrangement of the lever-arms B and C and their attachment to the trays and to each other the precise path of the trays may be varied, although its general characteristics, as hereinabove pointed out, will be preserved. When snow or ground plowed to a given depth or other soft and easily-yielding material is to be removed, the arrangement may advantageously be such as to give a long approach of the tray in the closing stroke in a position almost horizontal, yet at the end of the opening stroke giving a quick and sudden tilt to the trays to a nearly-vertical position, resulting in an effective dump. In Fig. 4 are shown three forms in which the excised material may be taken. Each form will be dependent on the path and inclination of the trays, which path and inclination may be secured, as above stated, by varying the arrangement, proportions, and relations of the arms B and C, the lower solid lines showing the form of cut made in ordinary soil when the parts are connected and related as shown in the drawings.

Numerous advantages are secured by the operation of an excavator constructed as herein described and shown, among the prin-

cipal of which may be mentioned the following: By the wide spread of the trays, of which our invention is capable, the device is able to 70 command a large space for making the cut. By giving the trays the most efficient inclination the entrance into the material is advantageously effected and by taking the load in a shallow cut over a large area the cut is 75 most easily made, and obstructions—such as roots, stones, and the like—are more easily overcome when near the surface. In such shallow long cut the bottom is left comparatively smooth and even, owing to the plowing 80 action, and not full of semispherical holes, and as a result of this in mining where it is desired to clean and scrape the bed-rock such shallow cut of the apparatus is most efficacious. The greater force with which the trays 85 are closed, owing to the action of its jointed closing mechanism, enables it to operate with ease in any kind of material, and from the form and inclination of the trays, the cutting edge only resting on the bottom when the load 90 is lifted, there is no suction to be overcome between the back of the tray and the bottom of the excavation. Finally, our improved device is free from latches or locks which are subject to derangement in such work, being 95 dependent only on simple levers or links swinging around pivot-pins, and is positive and efficient in its action.

We claim as our invention—

1. In an excavating apparatus, the combination with a pair of oppositely-disposed trays, of principal lever-arms pivotally connected with said trays, and auxiliary arms also pivoted to said trays in rear of the pivotal connection of said principal arms therewith and each extending to and connected with the principal lever-arm of the opposite tray, substantially as described.

2. In an excavating apparatus, the combination with a pair of oppositely-disposed trays, of principal lever-arms pivotally connected with said trays and with each other, said arms crossing each other intermediate their pivotal points in all positions of the trays, and auxiliary arms also pivoted to said trays and each extended to and connected with the proximate portion of the opposite principal arm, substantially as described.

3. In an excavating apparatus, the combination with a pair of oppositely-disposed trays, of principal lever-arms pivotally connected with said trays and with each other, said arms crossing each other intermediate their pivotal points in all positions of the trays, and auxiliary arms also pivoted to said trays in rear of the pivotal connection of said principal arms therewith and each extended to and connected with the proximate portion of the opposite principal arm, substantially as described.

4. In an excavating apparatus, the combination with a pair of oppositely-disposed trays, of principal lever-arms pivotally connected with said trays and with each other,

- auxiliary arms also pivoted to said trays and to the proximate portions of the principal lever-arms respectively, and means for closing the trays, said means comprising a pair of toggles 5 the outer ends of which are pivoted to the trays and to the opposite principal lever-arms respectively, and a suitably-guided cable connecting and drawing together the knees of the toggles, substantially as described.
- 10 5. In an excavating apparatus, the combination with a pair of oppositely-disposed trays, of principal lever-arms pivotally connected with said trays and with each other, auxiliary arms also pivoted to said trays and 15 to the proximate portions of the principal lever-arms respectively, and means for closing the trays, said means comprising a pair of oppositely-disposed toggles, the outer ends of which are pivoted to the noses of the trays 20 and the upper extremities of the principal lever-arms respectively, and a suitably-guided cable connecting and drawing together the knees of the toggles, substantially as described.
- 25 6. In an excavating apparatus, the combination with a pair of oppositely-disposed trays, of principal lever-arms pivotally connected with said trays and with each other, auxiliary arms also pivoted to said trays and 30 to the proximate portions of the principal lever-arms respectively, and means for closing the trays, said means comprising a pair of toggles the outer ends of which are pivoted to the trays and to the opposite principal 35 lever-arms respectively, guide-sheaves mounted at the knees of the toggles and near the pivotal connection of the principal lever-arms, and a suitable cable passing over said sheaves, substantially as described.
- 40 7. In an excavating apparatus, the combination with a pair of oppositely-disposed trays, of principal lever-arms pivotally connected with said trays and with each other, auxiliary arms also pivoted to said trays and 45 to the proximate portions of the principal lever-arms respectively, and means for opening the trays, said means comprising a pair

of oppositely-disposed toggles pivoted together at their outer ends, the knee of one of said toggles being at the pivotal connection 50 of the principal lever-arms, connections between the outer ends of the toggles and the trays, and a suitable cable connected to the knee of the other toggle, substantially as described.

55 8. In an excavating apparatus, the combination with a pair of oppositely-disposed trays, of principal lever-arms pivotally connected with said trays and with each other, auxiliary arms also pivoted to said trays and 60 to the proximate portions of the principal lever-arms respectively, and means for opening the trays, said means comprising a pair of oppositely-disposed toggles pivoted together at their outer ends and having means 65 connected therewith for effecting the simultaneous and equal movement of said toggles toward and past each other, the knee of one of said toggles being at the pivotal connection of the principal lever-arms, connections 70 between the outer ends of the toggles and the trays, and a suitable cable connected to the knee of the other toggle, substantially as described.

75 9. In an excavating apparatus, the combination with a pair of oppositely-disposed trays, of principal lever-arms pivotally connected with said trays and with each other, auxiliary arms also pivoted to said trays and 80 to the proximate portions of the principal lever-arms respectively, toggle mechanism connected to said trays through the actuation of which the trays may be opened, other toggle mechanism also connected to said trays by the actuation of which the trays may be 85 closed, and suitable cables connected to and actuating said toggle mechanisms, substantially as described.
